FIG. 1

FIG. 2

FIG. 3

FIG. 4

FIG. 5

FIG. 1 is a side elevational view of a convertible waste basket/step stool, showing my new design, the article being illustrated in normal upright position for use as a waste basket;

FIG. 2 is a side elevation thereof, viewed from a direction at right angles to the direction of FIG. 1;

FIG. 3 is a top plan view thereof;

FIG. 4 is a perspective view thereof; and

FIG. 5 is a perspective view thereof with the article in an inverted position for use as a step stool.

The sides opposite to those shown in FIGS. 1 and 2 are the same as the respective sides illustrated.

I claim:

The ornamental design for a convertible waste basket/step stool, substantially as shown and described.
